(57) **CLAIM**

The ornamental design for a shopping cart corral, as shown and described.

DESCRIPTION

FIG. 1 is a perspective view of a shopping cart corral in accordance with my new design;

FIG. 2 is a top plan view thereof;

FIG. 3 is a front end elevation view thereof;

FIG. 4 is a rear end elevation view thereof;

FIG. 5 is a left side elevation view thereof, the right side elevation view being a mirror image of the left side elevation view; and,

FIG. 6 is a bottom plan view thereof.

The dashed lines show environment and do not represent matter forming a part of my design.
